UNITED STATES PATENT OFFICE.

ANTHONY C. P. RUSSEN, OF EDGEWOOD, RHODE ISLAND.

THREAD-CONTROL ATTACHMENT FOR LOOMS.

Application filed June 5, 1923. Serial No. 643,488.

This invention relates to textile weaving machinery such as looms for lace making, rug weaving and kindred arts, and has for an object to provide an improved mechanism 5 for performing the functions of the jacquard cards and similar devices now generally employed with looms for weaving designs in the cloth, lace, rugs, and so forth.

It is a further object of the invention to 10 provide a device for this purpose which will be simpler in construction, cheaper to produce and operate, and which will be more reliable in operation.

It is a further object of the invention to 15 provide a control device for the threads in this type of mechanism which will be easier and cheaper to make than the jacquard cards, which will require less space and so may be more easily and cheaply stored when not in 20 use.

With the foregoing and other objects in view, I have devised the construction illustrated in the accompanying drawings, in which:

25 Fig. 1 is an elevation of a portion of a conventional loom mechanism showing my device applied thereto.

Fig. 2 is a detailed end elevation of the device on an enlarged scale.

30 Fig. 3 is a rear view of a portion of the same looking from the left of Fig. 2.

Fig. 4 is a top plan view showing the means for mounting the end of the drum supporting shaft.

35 Fig. 5 is a front view of the structure shown in Fig. 4.

Fig. 6 is a plan view of a portion of a strip of flexible material to be used with my attachment.

40 Fig. 7 is a similar view with a slightly different construction of strip which may be used with a square drum in place of the ordinary jacquard cards.

Fig. 8 is a partial plan and partial sectional view showing a slightly different construction of strip where projections are used instead of perforations.

45 As is well known, in the usual methods of weaving patterns or designs a series of relatively stiff cards are provided, each card being perforated according to a desired design to coat with the needle head of the loom to control the threads. These cards are laced together by a suitable lacing extending 50 through openings adjacent the opposite ends of the card, and each card is provided with

a relatively large opening at each end to receive positioning pins on the flat side of a square perforated drum which is used to advance the cards past the needle head by a step 60 by step movement, and also to advance the card against the ends of the needles in the thread controlling operation. These cards, however, are heavy and cumbersome, are expensive to make, and the operation of lacing 65 the cards is also an expensive one. The cards are heavy and require a large storage space. To overcome these objections I use in place of the separate cards laced together a continuous strip of flexible sheet material such 70 as paper, thin metal or some suitable fabricated substance. This continuous strip may also be used in place of the wooden bars with pegs or projected sheets used with certain types of textile machinery, that is, devices using a series of bars connected by chains having pegs that do tripping of needles, but in these cases, however, instead of perforating the control strip I propose to use in place of the perforations raised bumps 80 or projections, as shown in Fig. 8. In this case, however, the sheet would probably have to be made of thin metal.

Referring to the drawings, I have shown at 11 a series of harness threads connecting 85 the hooks 12 with the mechanism for lifting the warp threads, and the griff bar 13 for raising the hooks which are not moved out of alignment therewith by the needles 14 of the needle heads, the griff bars being raised 90 by any suitable mechanism as levers 15. As is well known each needle 14 controls a hook 12, and the needles are arranged in a number of horizontal rows, the number of rows and the number of needles in a row 95 depending on the design to be woven and the width of the repeat in inches.

In using my continuous flexible strips of sheet material for controlling the needles, I prefer to employ a round drum in place of the usual square drum used with the jacquard cards, although I may, if desired, employ my continuous strip with the square drum. When I employ the round drum I remove the square drum from the machine 105 and substitute my round drum, the support therefor and feeding mechanism in place of the square drum, and I have shown on the drawings an improved type of mechanism for using this continuous strip.

The supporting bars 16 are mounted to reciprocate in suitable bearings 17 on the

frame 18 of the loom and carry the usual square drum for use with the laced cards. These bars are reciprocated by suitable mechanism as a lever 19 connected to them by suitable links 20, and reciprocation of these bars press the cards against the needles and on the backward movement cooperate with mechanism for rotating the drum to advance the next card for the next operation.

10 I mount my improved attachment on these bars in place of the square drum.

This device comprises a carriage 21 provided with bearing lugs 22 to receive the bars 16 to which the carriage is securely connected. The carriage includes an upright backing plate 23 for the continuous strip of flexible material shown in dotted lines 24, this backing plate being provided with a series of horizontal rows of perforations 25, one for each of the needles 14 in the needle head, and at the opposite ends of this backing plate are guides 26 for the strip to hold it properly against the face plate. The carriage is provided with bearings 27, 28 for the shaft 29 for carrying the drum or drums 30. In the drawing I have shown two relatively narrow drums, one for each end of the continuous strip 24, but I can, and preferably do, use a third drum between these two drums for supporting the center of the continuous strip. Each drum is provided on its periphery with a series of pins or studs 31 adapted to enter a series of perforations 32 adjacent each edge and at the center of the continuous strips 24. The coaction of these pins and perforations properly position the strip before the backing plate 23 and the needles, and also serve to advance the strip upon rotation of the drums to bring the sets of perforations in the strip successively into cooperation with the needles.

The drums 30 are secured to the shaft 29 so as to rotate therewith and also secured to this shaft is a cam or ratchet disc 33 provided on its periphery with a series of shoulders or teeth 34 adapted to be engaged by a pawl 35 pivoted at 36 to one arm 37 of a bell crank lever fulcrumed on the shaft 29, the pawl being normally held in engagement with the periphery of the cam or ratchet disc 33 by a spring 38. The other arm 39 of the bell crank lever is provided with a slot 40 through which extends a pin 41 carried by a pivot lever 42. The lever 42 is fulcrumed on a pivot pin 43 secured in the frame 18 of the loom, and secured on this pivot pin is a pivot micrometer 44 having spaced arms 45 in which are threaded adjusting screws 46 engaging at their ends on opposite sides of a lug 47 carried by the lever 42.

The cam or ratchet disc 33 is also provided on its periphery with a plurality of flats 48 corresponding in number to the number of shoulders or teeth 34 and coacting with

these flats is a locking plate 49 held against the flats by a spring 50. The coaction of the plate 49 and its spring with these flats locks the drums in desired positions to hold them and the continuous strip 24 stationary and in proper position when the strip is advanced toward the needles.

The operation of this device is as follows:

The device is shown in the position spaced away from the levers with the drum and paper locked in position for cooperation with the needles. The carriage with the drum and continuous strip is now advanced toward the needle head, by reciprocation of the bars 16, pressing the strip 24 against the ends of the needles, but the ends of the needles which are in alignment with perforations in the strip passing through these perforations without being affected by the strip. The strip during this operation is held perfectly flat and backed up by the backing plate 23. During this movement to the right, as viewed in Fig. 2, to the dotted line position, as shown, the bell crank lever is rocked counter-clockwise on its pivot to the position shown in dotted lines which brings the pawl 35 in advance of the next shoulder or tooth 34 on the cam or ratchet disc 33 through the coaction of the pin 41 and slot 40. When the carriage is returned to its original position, as shown in full lines, coaction of this pin and slot will rotate the bell crank lever clockwise, as viewed in Fig. 2, and the pawl 35 will engage a shoulder of tooth 34 and advance the cam or ratchet plate a quarter revolution and with it the drum 30. During this operation the locking plate 49 will yield allowing the next flat 48 to be brought into engagement therewith so that the drum and with it the continuous strip of paper will be properly held in the next position. Thus it will be seen that the continuous strip is given a step by step feeding movement past the needles and each feeding movement is that required to bring the successive sets of perforations in the strip on the face of the backing plate 23 and in alignment with the needle head. In Figs. 6 and 7 I have indicated at 51 one set of these perforations, the number of rows, however, being different from that shown in 32 as it will be understood the number of rows of perforations will depend on the size of the design and the number of threads controlled. For the purpose of adjusting the effect of lever 42 on the bell crank during this reciprocating movement, the position of the pin 41 carried by this lever may be changed and secured in adjusted position by the screws 46.

In rug weaving there must be a definite start and finish due to the border, and therefore, in weaving rugs there must be sufficient of this perforated strip of paper, or other suitable substance, to cover the entire length

of rug, and it will, therefore, be in a continuous roll on a drum, and if it is to be used with a round drum as shown, it will be apparent from Fig. 6 that no space is required between the successive sets of perforations 51 as is the case where lacing of the cards is required, and therefore, the length of strip required for a given pattern with my continuous strip of flexible material is less than that required with a series of laced cards. As this continuous strip is not required to be as thick and heavy it will be apparent that there will be a great saving in the use of material and also in the amount of storage space required, to say nothing of the much greater ease in handling. The perforations shown at 75 are so called lift perforations and are used to control the lift of boxes with shuttles carrying different colored thread.

In weaving continuous cloth, however, the design is woven over and over, and therefore, I may use an endless strip of this flexible material, as paper or other desirable material, and use this endless continuous strip over and over during the weaving operation, a strip being of a length required for a single pattern or design. To facilitate the application of this endless strip to the machine and to allow insertion thereof in position without disconnecting it at any point, I mount one of the bearings 28 for the shaft 29 so that it may be moved to one side longitudinally of the shaft to allow the endless perforated strip to be placed on the drums. This construction is shown more clearly in Figs. 4 and 5 in which the bearing 28 is carried by a bracket 52 mounted to slide on suitable guides 53 carried by the carriage, the bracket being provided with suitable guideways for receiving the guides, and the bracket is secured in position by suitable clamping means such as a pin 54 threaded in the bracket and operated by means of a lever 55 to clamp a plug 56 against one of the guides 53. A guide plug 57 is also carried by the bracket having a rounded end 58 adapted to enter an opening in the carrier to properly center the bearing 28. When it is desired to remove an endless strip from the drum or apply one thereto, all that is required is to loosen clamp 54, slide the bracket 52 on the guide 53 to the left as viewed in Figs. 4 and 5, to the dotted line position, and then the strip may be removed from the drum and another strip slid onto the same passing down through the guideway or slot 59. The bracket 52 and bearing 28 are then returned to the full line position and clamped therein.

My continuous strip of flexible sheet material may also be employed with the square drums now used with the jacquard cards. For this purpose the sets of perforations

51, as shown in Fig. 7 are spaced to correspond with the spacing of the jacquard cards, and the continuous strip of paper or other material 24 is creased or scored at 60 transversely between these sets of perforations so that the strip will fold over the edges of the square drum and allow the portion of the strips between these folds or scores to lie flat on the flat sides of the drum. The strips represented by the portions between the folding or scoring are also provided with openings 61 to receive the positioning pin on the square drum. If it is desired to use this scored or folded strip with the round drum, as disclosed in Figs. 2 and 3, these drums are made somewhat larger in diameter than where the strip is not creased, as in Fig. 6, to allow for the required spacing between the sets of perforations, and the strip 24 is provided with rows of perforations 32 to coact with the studs or pins 31 of the drums the same as in the uncreased strip. Thus it will be seen that in order to use my continuous strip of paper, or other suitable flexible material, it is not necessary to provide a new or separate attachment for the loom but it may be employed with the square drum, and the saving in material, cost of making, and other desirable features may be gained without the necessity of using a round drum, although the round drum with the backing plate 23 is preferred. These continuous strips of paper, or other suitable flexible material, are much easier and less expensive to manufacture than the separate jacquard cards now used. They may be punched from a master roll automatically by machinery and as many copies as desired punched from one master roll. The machine for doing this will be described and claimed in a separate application.

In Fig. 8 I have shown how a continuous strip may be used to take the place of the wooden bars with pegs or projected sheets mentioned above. In this case the continuous strip 62 is made of thin sheet metal and instead of perforations is provided with lateral bumps or projections 63 to coact with the thread control needles.

Having thus set forth the nature of my invention, what I claim is:

1. In a loom having thread controlling means, a rotatable drum, means for rotating said drum with a step by step movement comprising a toothed ratchet, a pivoted lever, a pawl carried by said lever adapted to engage the ratchet teeth, flexible means controlled by said drum for cooperating with the thread controlling means, means for moving the drum toward and from the thread controlling means, and means operated by said movement for swinging said lever to rotate the drum comprising a normally stationary, pivotally mounted lever

connected to the first lever by a pin and slot connection, and means for adjusting the second lever about its pivotal mounting to vary the effect thereof on the first lever.

5. 2. In a loom having a frame and thread controlling means carried thereby, a carriage, means for moving the carriage toward and from the thread controlling means, a rotatable drum mounted on said carriage,

10 a toothed ratchet connected with said drum, a pivoted bell crank mounted on the carriage, a pawl carried by one arm of said bell crank and adapted to engage said ratchet, a lever pivoted to the frame and having pin and slot connection with the other arm of the bell crank, and means for adjusting said lever about its pivot and securing it in adjusted positions.

20 3. In a loom having a plurality of thread controlling needles, a carriage, a rotatable drum mounted on said carriage, a continuous strip of perforated flexible sheet material adapted to coact with said needles for controlling the threads, means for moving the carriage toward and from said needles, said carriage being provided with a perforated backing for the flexible strip opposed to the needles, a guide for the strip extending on the opposite side of the strip from said backing and movable therewith, and means for rotating the drum with a step by step movement to advance said strip.

25 4. In a loom having a plurality of thread controlling needles, a continuous strip of flexible sheet material provided with a plurality of sets of perforations, a backing plate for said strip provided with perforations arranged to correspond with the arrangement of the needles, means for advancing the strip over the backing plate with a step by step movement, means for moving the plate and strip toward and from the needles to cooperate therewith and guides for the strip on the opposite side of the strip from the plate and movable therewith.

30 5. In a loom having a plurality of thread controlling needles, a carriage, means for reciprocating the carriage toward and from the needles, a shaft, a drum mounted on the shaft, bearings for said shaft carried by the carriage, a guide carried by the carriage, a bearing for one end of the shaft mounted to slide on said guide, and means for clamping the bearing in position on said slide.

35 6. In a loom having a plurality of thread controlling needles, a carriage, a rotatable drum mounted on said carriage, a perforated pattern running over said drum and adapted to coact with said needles for controlling the threads, means for moving the carriage toward and from said needles, a

perforated backing member for the pattern carried by the carriage and opposed to the needles, a guide for the pattern forwardly of said backing member and movable therewith, and means for rotating the drum with a step by step movement to advance the pattern over said backing member.

70 7. In a loom having a frame and thread controlling means carried thereby, a carriage, means for moving the carriage toward and from the thread controlling means, a rotatable drum mounted on said carriage, a toothed ratchet connected with said drum, a pivoted lever mounted on said carriage, a pawl carried by said lever and adapted to engage said ratchet, and a connection from said lever to the frame to swing said lever on its pivot by movement of the carriage.

75 8. In a loom having a frame and thread controlling means carried thereby, a carriage, means for moving the carriage toward and from the thread controlling means, a rotatable drum mounted on said carriage, a toothed ratchet connected with said drum, a pivoted lever mounted on said carriage, a pawl carried by said lever and adapted to engage said ratchet; a second lever pivoted to the frame and having pivoted and sliding connection to the first lever, and means for adjusting the second lever about its pivot and securing it in adjusted positions.

90 9. In a loom having a frame and thread controlling means carried thereby, a carriage, means for moving the carriage toward and from the thread controlling means, a rotatable drum mounted on said carriage, a toothed ratchet connected with said drum, a pivoted lever mounted on said carriage, a pawl carried by said lever and adapted to engage said ratchet, a second lever pivoted to the frame and having pivoted and sliding connection to the first lever, a lug connected with the second lever, and adjusting screws carried by the frame and engaging opposite sides of said lug.

95 10. In a loom having a frame and thread controlling means carried thereby, a carriage, means for moving the carriage toward and from the thread controlling means, a rotatable drum mounted on said carriage, a toothed ratchet connected with said drum, a pivoted lever mounted on said carriage, a pawl carried by said lever and adapted to engage said ratchet, a connection from said lever to the frame to swing said lever on its pivot by movement of the carriage, said ratchet being provided with a plurality of flats, and a spring pressed block arranged to engage 115 said flats to hold the drum in different positions.

In testimony whereof I affix my signature.

ANTHONY C. P. RUSSEN.
